CLAIM

The ornamental design for an adjustable kicking pad holder, as shown and described.

DESCRIPTION

FIG. 1 is a perspective view;
FIG. 2 is an enlarged top view, the bottom view being a mirror image of this;
FIG. 3 is a front view;
FIG. 4 is a back view;
FIG. 5 is a right side view; and,
FIG. 6 is a left side view.
The broken line showing of the kicking pad is for illustrative purposes only and forms no part of the claimed design.
